UNITED STATES PATENT OFFICE.

FRANCIS M. GRAHAM, OF SAN JOSÉ, CALIFORNIA.

WAVE-MOTOR.

SPECIFICATION forming part of Letters Patent No. 592,051, dated October 19, 1897.

Application filed January 13, 1897. Serial No. 619,065. (No model.)

To all whom it may concern:

Be it known that I, FRANCIS M. GRAHAM, a citizen of the United States, residing at San José, in the county of Santa Clara and State 5 of California, have invented certain new and useful Improvements in Wave-Motors; and I do hereby declare that the following is a full, clear, and exact description thereof.

This invention relates to certain new and 10 useful improvements in wave-motors; and it consists in the arrangement of parts and details of construction as will be hereinafter fully shown in the drawings and described and pointed out in the specification. In the 15 ordinary wave-motor the float is not raised to the full height of the wave operating the same, for the reason that the wave travels with such speed that it begins to recede before the float has been carried its full stroke 20 or height. By this failure of the float or weight to move the full upward distance of the wave, the rise and fall movement of the said float or weight is considerably limited.

It is the object of my invention to construct 25 the wave-motor so that the wave cannot recede until after the float or weight has been raised to the full height thereof.

In order to understand my invention fully, 30 reference must be had to the accompanying sheet of drawings, wherein—

Figure 1 is a vertical sectional view showing the arrangement of the floats within the casing. Fig. 2 is a side view in elevation, the casing being partly broken away, showing the connection between the slide-rods located within the casing and the vertically-movable rods secured outside of the casing, and the connection between said rods and the fulcrumed catches for the swinging doors or 35 gates hinged within openings in one side of the casing; and Fig. 3 is a sectional top plan view taken on line $x-x$, Fig. 1.

In the drawings, the letter A is used to indicate the closed casing, which casing is 40 rigidly secured or anchored in any suitable manner. In the bottom of the casing are formed the inlet-openings a' , said openings being closed by the hinged valves a . In one of the sides of the casing are formed the 45 openings 1 2 3. Within these openings are hinged the gates or doors 4 5 6, which gates

or doors are hinged so as to swing inward and outward.

Within the casing A is located the main float or weight B, which float or weight is connected to any suitable power mechanism by means of the chain or cable B'. Above the weight or float B is placed the auxiliary float B², which is made lighter than the float B and moves freely upon the chain or cable, said 55 chain or cable passing through a central vertical opening in the float B². Each float or weight moves between the vertical guide-rods C C', and is held thereto by means of the corner-straps b. Within the casing A are located the vertical rods C², said rods being 60 movable toward or from the sides of the casing containing the hinged gates or doors 4 5 6. The vertical rods C² work at each end in the guide-plates h, secured at the top and bottom of the casing A, Fig. 1.

To the outside of the casing A are secured the vertically-movable rods D. These rods work through the ears b', projecting from the casing, and each rod is connected to the 75 latches D', fulcrumed to the edges of the said casing, by means of the studs b² projecting from the rods fitting within the slot b', formed in the tail of the latch D'. The rods being thus connected, it is obvious that as the rods 80 D are raised or lowered the latches D' will turn upon their fulcrumed point, so as to unlock or lock the doors or gates 4 5 6. The position of the latches, when the gates or doors are locked against outward movement, is illustrated by Fig. 2 of the drawings.

Through an opening d, formed in two sides of the casing, extends the crank-rod d'. One end of each rod is rigidly connected to one of the vertical rods C², while the free end of the 90 rod is downwardly inclined and works beneath the stud d², projecting from the vertically-movable rods D. As the rods d' are moved beneath the studs d², by the outward movement of the rods C², the studs d² ride 95 upon the inclined portion of the crank-rods d' and the rods D are gradually raised. During the upward movement of these rods the latches D' gradually turn upon their fulcrumed point, so as to unlock the gates or 100 doors 4 5 6. The rods C² are moved outward, so as to cause the crank-rods d' to raise the

rods D in order to unlock the gates or doors 4 5 6, by means of the levers E, fulcrumed to the main float or weight B. The lower end of each lever terminates in a claw e, which 5 embraces the rods C². As these fulcrumed levers are straightened out the rods C² will be forced outward.

As the wave strikes against the casing the valves a are opened inwardly and the water 10 rushes into the casing through the openings a' and the openings of the doors or gates 4 5 6, said gates swinging inward with the pressure of the water. The gates 4 5 6 being locked against outward movement, it is obvious 15 that, while the water is free to enter the casing, it cannot escape therefrom until the said gates are released or unlocked. The water rushing into the casing causes the lighter float B² to rise to its full height. The 20 lower or heavier float, owing to the water being confined, gradually rises to the top of the water within the casing. As the lower float is raised to the surface of the water, the upper float will rest thereon, bearing with its 25 full weight upon the upper end of the levers fulcrumed to the said lower float. While the upper float is considerably lighter than the lower float, it is nevertheless of sufficient weight to cause the levers E, when resting 30 thereon, to force the rods C² outward in order that the crank-rods may lift the rods D, so as to throw the latches and unlock the doors or gates 4 5 6, so that the pressure of 35 the retained water will swing the said gates outward as the water escapes from within the casing. As the water escapes from within the casing the floats B and B² will gradually move toward the bottom of the casing. In order that the movement of the valves a may 40 not be interfered with, the weight or float B

does not at any time rest upon the bottom of the casing, but, when at rest, is held a short distance above the bottom.

Having thus described my invention, what I claim as new, and desire to secure protection 45 in by Letters Patent, is—

1. In a wave-motor, the combination with the fixed casing, water - openings formed through the bottom and side of the casing, of the inwardly-moving valves controlling the 50 openings in the bottom of the casing, the gates hinged to swing within the side openings of the casing, the lock devices for said gates, the two floats located within the casing and connection between the lock devices and the 55 upper float.

2. In a wave-motor, the combination with the fixed casing, having water-openings in the bottom and side thereof, the valves controlling the openings in the bottom, hinged 60 gates closing the side openings, the main float located within the casing, an auxiliary float placed above the main float, the levers fulcrumed to the main float, the rods movably secured within the casing, said rods being 65 operated by the movement of the fulcrumed levers, the vertically-movable rods secured to the outside of the casing, connection between said rods and the movable rods within the casing, the lock devices for the swinging 70 gates and connection between said lock devices and the vertically-movable rods.

In testimony whereof I affix my signature, in presence of two witnesses, this 23d day of December, 1896.

FRANCIS M. GRAHAM.
